United States Patent Office.

WILLIAM F. RUNDELL, OF GENOA, NEW YORK.

Letters Patent No. 79,009, dated June 16, 1868.

IMPROVEMENT IN HARVESTER-REELS.

The Schedule referred to in these Letters Patent and making part of the same.

TO ALL WHOM IT MAY CONCERN:

Be it known that I, WILLIAM F. RUNDELL, of Genoa, in the county of Cayuga, and State of New York, have invented a new and improved Reel for Reaping and Mowing-Machines; and I do hereby declare that the following is a full, clear, and exact description thereof, which will enable those skilled in the art to make and use the same, reference being had to the accompanying drawings forming part of this specification.

This invention relates to an improvement on a reel for reaping and mowing-machines, for which reel, Letters Patent have just been granted to me, dated December 31, 1867.

The present invention consists in a modification of the elbows by which the beaters are secured to the arms, whereby said beaters may be tightened or firmly secured to the arms in the event of becoming loose by shrinkage. In the accompanying sheet of drawings—

Figure 1 is an end view of my invention.

Figure 2 a section of the same, taken in the line xx , fig. 1.

Similar letters of reference indicate corresponding parts.

A represents the reel-shaft, turned down at one end to form a tenon and shoulder, on which a three-socket head, B, is fitted, said sockets designated by a , being at equal distances apart, and open at their ends and inner sides to receive the arms C of the reel.

These arms, as in the original patented device, may be of wood, and they are firmly secured in the sockets by a plate, D, which is firmly screwed up against them by a screw-nut, a^x .

Longitudinal movement of the arms C, may, if necessary, be prevented by studs or pins b in the sockets, as in the original invention.

E represents metallic elbows, each composed of two longitudinal parts, of right-angular form, and constituting sockets to receive the outer parts of the arms C, and the inner parts of the beaters F, the latter, like the arms, being of wood.

The arms C are secured in one part of the elbows by screw-bolts c , which pass transversely through the arms, and both parts of the elbows and the beaters F are secured in the other part of the elbows by similar bolts d , (see more particularly fig. 1.)

The two parts of the elbows are not allowed to come in contact with each other, and hence, in case of the shrinking of the wood, the arms and beaters, by screwing up the nuts of the bolts c d , may be firmly clamped and held.

This is a great improvement over my former invention, in which no provision was made for the tightening of the arms and beaters in case of shrinkage, which always occurs in a greater or less degree.

The beaters are made of taper-form, gradually decreasing in thickness from the arms C towards their outer ends, in order to insure lightness.

I claim as new, and desire to secure by Letters Patent—

The constructing of the elbows E of two longitudinal parts, with bolts passing transversely through the two parts, and also through the arms and beaters, substantially in the manner as and for the purpose herein set forth.

WM. F. RUNDELL.
